UNITED STATES PATENT OFFICE.

THOMAS WEBBER COTTLER, OF OAKLAND, KANSAS.

DECK SASH AND TRANSOM.

1,037,134.

Specification of Letters Patent. Patented Aug. 27, 1912.

Application filed April 27, 1911. Serial No. 623,649.

To all whom it may concern:

Be it known that I, THOMAS W. COTTLER, a citizen of the United States, and a resident of Oakland, in the county of Shawnee and 5 State of Kansas, have made certain new and useful Improvements in Deck Sashes and Transoms, of which the following is a specification.

My invention relates to improvements in 10 deck sashes and transoms, and it consists in the combinations, constructions and arrangements herein described and claimed.

An object of my invention is to provide 15 a transom which may be used in railway cars and which may be opened or closed by a single movement and when closed will be positively locked in position.

A further object of my invention is to 20 provide a sash which may be readily removed, and which, when removed, may be placed in a pile of other similar sashes without danger of breaking the glass since there are no projecting members that are liable to come into contact with the glass.

25 A further object of my invention is to provide a sash which may be opened to permit ventilation and which may be held in open position by simple and inexpensive means.

30 Other objects and advantages will appear in the following specification, and the novel features of the device will be particularly pointed out in the appended claims.

My invention is illustrated in the accompanying drawings, in which—

Figure 1 is a perspective view showing one embodiment of my invention, Fig. 2 is a side view of the transom, a portion of the transom casing being shown in section, 40 Fig. 3 is a section along the line 3—3 of Fig. 2, Fig. 4 is a section along the line 4—4 of Fig. 2, Fig. 5 is a perspective view of the guide lug, and Fig. 6 is a detail section of the spring holding means for the 45 guide lug.

Referring now to Figs. 1 and 2, it will be seen that I have provided a sash having a horizontal portion 1, a vertical portion 2, and an arc shaped portion 3, the said sash 50 being arranged to receive the pane of glass 4, and to fit in the opening in the casing 5.

Referring to Fig. 2, I have shown therein a small plate 6 which is screwed to the casing 5 and which is provided with a 55 pin 6^a arranged to project into a slot 1^a in the end of the bottom member 1. The op-

posite end of the sash is provided with a similar slot 1^b arranged to receive a similar pin 6^b. The pins 6^a and 6^b form pivotal supports upon which the sash may turn. 60

The member 2 is provided with a cutaway portion 2^a, and is recessed to receive a plate 7 having an integral member 7^a in which is disposed a plunger 7^b held normally in an inner position by means of a spring 7^c (see 65 Fig. 5). The plunger stem carries a lug 8, which is provided with shoulders 8^a and 8^b, these shoulders being beveled as shown at 8^x (see Fig. 6). The link 9 is pivotally secured at one end by means of a screw 10^a to the window casing 5. The link is provided with a longitudinal slot 9^a arranged to receive the central portion of the lug 8. The beveled shoulders 8^x of the lug are adapted to enter transverse notches 9^x in the reduced portions 9^x and 9^y which are adjacent to the longitudinal slot 9^a. 70

75 The locking device is best shown in Fig. 4. It consists of a plate 10 to which is pivotally secured a locking member 11. The latter is provided with a loop or eye 11^a on one end and a shoulder or projection 11^b at its opposite end. Normally the catch or shoulder 11^b lies in an opening 12^a in a plate 12 which is secured to the casing 5. This end of the 80 catch, however, may be swung out of the opening 12^a into the recess 3^a in the sash member 3 against the tension of the 85 spring 14.

90 From the foregoing description of the various parts of the device, the operation thereof may be readily understood.

When the sash is closed the latch 11 is in the position shown in Fig. 4. In this position it will be seen that the sash is in contact with the weather strip 13 which is secured to the casing 5. The sash is held securely in this position by the latch 11. All that is required to open the sash is to insert a hook in the eye 11^a and to pull. This may be done 100 by one on the floor of the car in the ordinary manner. The effect is, first, to cause a withdrawal of the latch member 11^b from the socket 12^a and then the movement of the sash on the pins 6^a and 6^b. Since the link 9 is pivoted it will permit the sash to take an inclined position like that shown in Fig. 3, the guide lug 8 turning on its pivot. The sash will be held by the engagement of the beveled shoulders 8^a on the lug 8 in the groove 9^x. Force exerted on the sash in either direction, however, will cause the 105 110

spring lug 8 to ride out of the groove so that the sash may be closed or opened.

In order to shut the sash it is only necessary to push it back into position when the 5 lock will again spring into place by reason of the spring 14, thus locking the sash securely into position.

If it is desired to remove the sash, the 10 screw 10 may be removed from the link 9. The sash may be swung down into a horizontal position and a slight pull will cause it to leave the pivotal pins 6^a and 6^b. A number of the sashes may then be piled one upon 15 the other without any danger of breaking the glass in the sashes.

I claim:

The combination with a transom casing, 10 of a pivoted sash therefor having a recess, a pivoted link secured to the casing, and 20 adapted to lie within the recess of said sash

when the latter is closed, said link being provided with a longitudinal slot and transverse slots extending laterally from said longitudinal slots, a guide lug having a rectangular portion arranged to enter the longitudinal slot in said link and being provided with laterally extending portions having beveled edges arranged to enter the transverse slots on both sides of said longitudinal slot, said sash being provided with a recess, a 25 stem secured to said lug and being provided with a head, said head and said stem being disposed in the recess in said sash, and a spring arranged to engage the head for yieldingly securing the lug. 30
